[57] CLAIM

The ornamental design for a collapsible photographic camera, substantially as shown and described.

DESCRIPTION

FIG. 1 is a front elevational view of a collapsible photographic camera, showing our new design and shown in the open position thereof;

FIG. 2 is a left-side elevational view thereof;

FIG. 3 is a front elevational view shown in the collapsed position;

FIG. 4 is a left-side elevational view thereof; and

FIG. 5 is a perspective view thereof.

The appearance of the side of the collapsible photographic camera not shown in the drawing is identical with the appearance of the side shown in FIGS. 2 and 4, respectively, except for the absence of the knob shown in these FIGS. 2 and 4.

The top and rear surfaces of the device, which are not disclosed, are substantially planar and unornamented.
